LATCH SHAFT FASTENING MEANS

Filed Sept. 29, 1926

UNITED STATES PATENT OFFICE

WILLIAM C. DEVEREAUX, OF DETROIT, MICHIGAN

LATCH-SHAFT-FASTENING MEANS

Application filed September 29, 1926. Serial No. 138,384.

This invention relates to means for fastening the shafts of latches for vehicle doors, etc., and has for its principal object the provision of simple means for removably securing latch shafts to turnable portions of the latches without use of screws, bolt or the like.

Another object of my invention is the arrangement of a latch shaft carrying latching means whereby it may be secured to the hub 10 of the actuating cam of the latch by merely inserting the shaft into the aperture of the hub.

A further object of my invention is the provision of a latch shaft carried by the latch handle, a portion of the latch shaft being surrounded by an ornate spacer tube adapted to slidably fit within a centrally apertured escutcheon plate carried by the vehicle door, whereby substantially the same appearance 20 of door handle and adjacent parts is secured despite different thicknesses of vehicle doors. There is a commercial tolerance in automobile body building whereby the thickness of doors intended for the same model cars may 25 vary as much as one-eighth of an inch. With my improved latch shaft assembly it is possible to utilize the same latch shaft with doors varying the permissible limit and yet obtain substantially the same appearance adjacent the latch handle, the spacer tube merely 30 extending within the escutcheon plate for different distances.

A further object of my invention is the provision of a latch shaft assembly for vehicle doors and the like whereby the usual escutcheon plate secured to the vehicle door by screws or like fastening means is eliminated. Heretofore the body escutcheon plate has been assembled with two screws passing 40 through the escutcheon plate into the panel of the door. With covered wood doors it has been necessary to maintain sufficient wood adjacent the latch shaft to provide security for the screws, and with all-steel doors it has been necessary to weld a tapping plate to the body panel to accommodate the escutcheon plate screws. The welding of the tapping plate to the panel, cleaning off weld marks on the body panel preparatory to the finish 50 and the time required to assemble the es-

cutcheon plate, latch shaft and handle, are all expensive, and these costs are eliminated by my new construction. Moreover, in the assembly of the old type escutcheon plate attached by screws the escutcheon plate was 55 fitted so tight upon the vehicle door that often the finish was cracked by the edges of the escutcheon plate. Such marring of the finish has been especially prevalent since automobile bodies have been finished in Duco or 60 similar lacquer finishes. My improved latch shaft assembly obviates these objections to the old escutcheon plate arrangement. Again, there is an advantage in appearance 65 in my improved door handle assembly over the old type of screw-on escutcheon plate, as no means of security such as screws is visible.

Other objects and advantages will be apparent from the following description, 70 wherein reference is made to the accompanying drawings illustrating preferred embodiments of my invention and wherein similar reference numerals designate similar parts throughout the several views. 75

In the drawings:

Fig. 1 is an elevation of a latch for vehicle doors adaptable for use with my improved latch shaft and door handle assembly.

Fig. 2 is a horizontal sectional view 80 through a vehicle door equipped with my improved door handle assembly and latch shaft, the latch shaft being secured to a turnable portion of the latch.

Fig. 3 is an enlarged detail sectional view 85 through the latch casing, the hub of the actuating cam of the latch and the adjacent portion of my improved latch shaft with a tool holding the latch pin of the latch shaft in retracted position, and 90

Figs. 4 and 5 are detail sectional views 95 through the latch casing, hub of the actuating cam of the latch and adjacent portions of the latch shaft, the latch shaft being secured to the hub by slightly modified arrangements of latching means.

Referring now to the drawings, the numeral 5 designates a portion of a vehicle door and 6 a latch casing adapted to be secured to the door by means of screws 7 or 100

like fastening means. The latch casing 6 carries a slideable latch bolt 8 having a portion normally extended beyond the latch casing by means of a spring 9 or the like. The extended portion of the latch bolt 8 is adapted to engage a striker plate (not shown) carried by the door jamb. The latch bolt 8 is adapted to be withdrawn to free its extended portion from engagement with the striker plate by means of an actuating cam 10 mounted in the latch casing and engaging an offset arm 11 carried by the latch bolt. The actuating cam 10 is adapted to be rotated by a latch shaft 12 carried by the door handle 13 which is usually arranged on the outer side of the vehicle door. In addition a vertical spindle 14 may be arranged with its handle 15 adjacent the inner side of the vehicle door to enable the ready unlatching of the door by persons within the vehicle. As herein shown the spindle 14 is provided with a crank portion 14^a adapted to contact a shoulder 8^a on the latch bolt, a light spring 16 being arranged to normally urge the crank portion of the spindle away from the shoulder 8^a.

The parts above described may vary in many particulars, and are intended to show one embodiment of vehicle door and latch with which my improved latch shaft and door handle assembly is useful. The illustrations of the above described parts are merely for purposes of exemplification, and it is to be understood that the claimed invention herein is adaptable for use with other forms of latches, etc.

My improved latch shaft is formed with a bore 12^a extending partway through the latch shaft and preferably obliquely arranged relatively to the side faces of the latch shaft. Within the bore 12^a is arranged a light spring 17 and a latching pin 18, the spring being adapted to abut against the inner extremity of the latching pin and the bottom wall of the bore 12^a. After the latching pin 18 has been inserted within the bore 12^a, the diameter of the outer extremity of the bore is reduced, as by peening the surface of the latch shaft adjacent the bore, so that a stop is provided for the outward movement of the latch pin because of the pressure of the spring 17 and to prevent the latching pin from accidentally flying out of the bore. The latch pin 18 is preferably provided with a curved outer extremity and the stop for the latch pin is preferably so arranged that a sufficient portion of the latch pin normally extends beyond the side face of the latch shaft to permit the entrance of the extended portion of the latch pin into the latching aperture 19 in the hub 10^a of the actuating cam 10 when the extended portion of the latching pin is in alignment with the aperture 19. By virtue of this construction the latch shaft 12 may be secured to the hub 10^a of the actuating cam 10 by merely inserting the latch shaft through

the aperture 20 in the door 5 and into the hub of the cam until the latching pin 18 snaps into the latching aperture 19 of the cam. As the latch bolt is being inserted the latch pin is depressed by engagement with that portion of the hub 10^a in advance of the latching aperture 19, the curved surface of the extending portion of the latching pin serving to readily permit the depression of the latching pin upon engagement with the hub. To guide the latch shaft 12 into the central aperture of the hub 10^a as well as to aid in the depression of the latching pin 18 during the insertion of the latch shaft the forward portion of the cam is preferably provided with a circular groove 10^b having an inclined rear wall leading into the central aperture of the hub 10^a of the cam. After the latch shaft has been inserted into the central aperture of the cam 10^a and latching pin snaps into the latching aperture 19 in the cam oscillation of the latch shaft in the proper direction will serve to turn the cam 10 to retract the latch bolt to withdraw its extended portion out of engagement with the striker plate. Then upon release of the pressure upon the latch shaft to turn it in such direction, the spring 9 will serve to return the latch bolt, cam 10 and latch shaft to their original positions. To aid in the simultaneous turning movements of the latch shaft 12 and cam 10, the central aperture of the cam is preferably made of the same shape as the latch shaft, as for example, square in cross section (note Fig. 1).

When it is desired to remove the latch shaft 12 from the cam 10 it is necessary to first retract the latching pin 18 from its position within the latching aperture 19 of the cam. This may be accomplished by inserting a tool 21 through an aperture 22 in the latch casing 6 arranged in alignment with the latching aperture 19 (note Fig. 3) and through the latching aperture 19 into engagement with the latching pin 18. Sufficient pressure upon the tool 21 will force the latching pin within the bore 12^a against the tension of the light spring 17, whereupon the latch shaft 12 may be withdrawn from the central aperture of the hub 10^a of the cam.

From the above it will be apparent that the latch shaft 12 may be quickly fastened within the hub 10^a of the cam without the use of screws, bolts or like fastening means, and may be as readily removed therefrom.

A spacer tube 23 is preferably secured to the handle 13 and surrounds the portion of the latch shaft 12 adjacent the handle. The spacer tube 23 may be variously shaped for ornamental purposes and its outer surface may be nickelized or otherwise finished to conform with the decorative finish of the vehicle with which it is used. The rear portion of the spacer tube 23 extends within an escutcheon plate 24, substantially as shown in Fig. 2, which escutcheon plate may be of various or

nemental shapes and its outer surface nickelized or otherwise finished as desired. The escutcheon plate 24 is preferably formed with ears 24^a on its rear extremity adapted to fit within slots 25 cut in the metal cover plate 5^a of the vehicle door 5. The overlapping arrangement of escutcheon plate 24 and spacer tube 23 permits the use of latch shafts 12 of the same length with doors 5 of different widths, the rear portion of the spacer tube 23 extending different distances within the escutcheon plate 24 in accordance with the variations in thickness of the door 5. Moreover, the appearance of the handle, spacer tube and escutcheon plate extending beyond the inner face of the door 5 will remain substantially the same despite the differences of extension of the spacer tube within the escutcheon plate. A coil spring 26 may be arranged to press the handle 13 outwardly as far as permitted by the latching pin 18 and also to aid in securing the escutcheon plate in position upon the face plate 5^a of the door. Such arrangement also aids in preventing noise due to chatter between loosely fitting parts of the latch shaft assembly as well as enabling the use of the same latch shaft assembly with cams 10 having central apertures of different areas. As herein shown a washer 27 is arranged between the forward extremity of the spring 26 and the rear extremity of the spacer tube 23 to permit the oscillation of the spacer tube and latch shaft without oscillating the spring 26. Moreover, this arrangement of latch shaft and door handle assembly permits the use of a comparatively light spring 26 which greatly lessens the friction between the several parts of the assembly, thus necessitating far less adjusting to secure a free working door latch and handle. The old type handle and latch shaft arrangement had to have a stiff spring placed between the body panel and the under part of the handle escutcheon to prevent noise and this spring has been the cause of considerable friction between the old type escutcheon and spacer tube. In many instances this friction could not be overcome by the main spring 9 of the latch bolt 8 on which it depended to throw the handle back into normal position after the latch bolt had been retracted to permit opening of the door. My improved arrangement of latch shaft and door handle assembly permits the use of a spring 26 adjacent the door handle that is very light compared to the main spring 9 of the latch bolt 8.

In Fig. 4 is shown a slightly modified form of latching pin arranged in substantially the same manner within the bore 12^a as the latching pin 18 shown in Figs. 1-3. The latching pin 18^a shown in Fig. 4 is provided with a circumferential groove 18^b arranged so that when the latching pin is positioned within the locking aperture 19 of the cam hub the forward wall of the aperture 19 will fit within

the groove 18^b. This provides additional security against the accidental disconnection of the latch shaft and cam hub.

In Fig. 5 is shown another embodiment of latching means between the latch shaft 12 and the cam hub 10^a consisting of a ball 28 arranged within the bore 12^a and pressed outwardly by the pressure of the spring 17. The ball 28 has the advantages of being cheaper to manufacture than the latching pin shown in Figs. 1-4, and also is adapted to present new surfaces into engagement with the walls of the latching aperture 19 during continued use. Moreover, the ball 28 will readily ride over the forward portion of the cam hub 10^a during the insertion of the latching bolt into the cam hub.

While it will be apparent that the illustrated embodiments of my invention herein disclosed are well calculated to adequately fulfill the objects and advantages primarily stated, it is to be understood that the invention is susceptible to variation, modification and change within the spirit and scope of the subjoined claims.

Having described my invention, I claim

1. In a latch, a latch bolt, a turnable part for moving the latch bolt and having a latching aperture therein, and a latch spindle carrying an obliquely disposed spring-pressed projecting member adapted to enter said latching aperture to secure the spindle to the turnable part by sliding therein, but to resist removal of engagement of its side against the side of the latching aperture.

2. In a latch, a latch bolt, a turnable part for moving the latch bolt having a central aperture therein and a latching aperture opening into said central aperture, and a latch spindle adapted to enter said central aperture and carrying an obliquely disposed spring-pressed projecting member adapted to enter said latching aperture upon sliding the spindle into the central aperture, and to prevent removal of the spindle by engagement of its side against the side of the latching aperture.

3. In a latch, a latch bolt, a turnable part for moving the latch bolt having a central aperture therein and a latching aperture opening into said central aperture, and a latch spindle adapted to enter said central aperture, said latch spindle having an obliquely disposed bore therein, a spring arranged in the bore and a latching pin slidable in the bore and adapted to project beyond the side face of the latch spindle into said latching aperture, and to retain itself and the spindle in the position thereby determined by engagement of a slanting surface of the latching pin against the side of the latching aperture.

4. In a latch, a latch bolt, an actuating cam for moving the latch bolt having a central aperture therein and a latching aperture opening into said central aperture, and a

latch spindle adapted to enter said central aperture, said latch spindle having an obliquely disposed bore therein, a spring arranged in the bore and a latching pin slidable in the bore and adapted to project beyond the side face of the latch spindle into said latching aperture, and to retain itself and the spindle in the position thereby determined by engagement of a slanting surface of the latching pin against the side of the latching aperture.

5. The combination with a door having an elongated passage therethrough, a latch casting secured upon the door and having an actuating cam provided with a central aperture arranged in alignment with said elongated passage, and a latching aperture opening into said central aperture, a latch spindle extending through said passage and into the central aperture of said cam, said latch spindle carrying an obliquely disposed spring-presser latching pin adapted to enter said latching aperture of the cam and to retain itself and the spindle in the position thereby determined by engagement of a slanting surface of the latching pin against the side of the latching aperture.

6. The combination with a door having an elongated passage therethrough, a latch casting secured upon the door and having an actuating cam provided with a polygonal central aperture arranged in alignment with said elongated passage, and a latching aperture angularly disposed to and opening into said central aperture, a latch spindle having a polygonal portion extending through said passage and into the central aperture of said cam, said latch spindle carrying a spring-pressed latching pin arranged obliquely with relation to the sides of the shaft and adapted to enter said latching aperture of the cam, and to retain itself and the spindle in the position thereby determined by engagement of a slanting surface of the latching pin against the side of the latching aperture.

7. The combination with a door having an elongated passage therethrough, a latch casting secured upon the door and having an actuating cam provided with a central aperture arranged in alignment with said elongated passage and a latching aperture opening into said central aperture, a latch spindle extending through said passage and into the central aperture of said cam, said latch spindle carrying a spring-pressed latching pin adapted to enter said latching aperture of the cam, the actuating cam being provided with a flaring groove surrounding the central aperture for guiding the latch spindle and latching pin during the insertion thereof into the cam.

8. The combination with a door having an elongated passage therethrough, a latch casting secured upon the door and having an actuating cam provided with a central aperture

arranged in alignment with said elongated passage, and a latching aperture opening into said central aperture, a latch spindle extending through said passage and into the central aperture of said cam said latch spindle carrying a spring-pressed latching pin adapted to enter said latching aperture of the cam, the latch spindle also carrying a handle and a spacer tube, and an escutcheon plate arranged between the handle and door and having a central aperture therein for the reception of a portion of said spacer tube.

9. The combination with a door having an elongated passage therethrough, a latch casting secured upon the door and having an actuating cam provided with a central aperture arranged in alignment with said elongated passage, and a latching aperture opening into said central aperture, a latch spindle extending through said passage and into the central aperture of said cam, said latch spindle carrying a spring-pressed latching pin adapted to enter said latching aperture of the cam, the latch spindle also carrying a handle and a spacer tube, an escutcheon plate arranged between the handle and door and having a central aperture therein for the reception of a portion of said spacer tube, and a spring arranged between the escutcheon plate and spacer tube for holding the escutcheon plate against the door and exert pressure upon the latch spindle to maintain the latching pin in engagement with the wall of said latching aperture nearest the handle.

10. The combination with a door having an elongated passage therethrough, a latch casting secured upon the door and having an actuating cam provided with a central aperture arranged in alignment with said elongated passage, and a latching aperture opening into said central aperture, a latch spindle extending through said passage and into the central aperture of said cam, said latch spindle carrying a spring-pressed latching pin adapted to enter said latching aperture of the cam, the latch spindle also carrying a handle and a spacer tube, an escutcheon plate arranged between the handle and door and having a central aperture therein for the reception of a portion of said spacer tube, a spring surrounding the latch spindle and adapted to press the escutcheon plate into engagement with the door, and a washer surrounding the latch spindle and arranged between said spring and spacer tube.

In witness whereof I hereunto set my hand.
WILLIAM C. DEVEREAUX.
